HIGH CURRENT BUSHING

Thomas F. Brandt, Barberton, Ohio, assignor to
 The Ohio Brass Company, Mansfield, Ohio, a
 corporation of New Jersey

Application October 12, 1935, Serial No. 44,761

3 Claims. (Cl. 173—318)

This invention relates to high current electric bushings, and has for one of its objects the provision of a bushing insulator having a heavy conductor extending entirely through the insulator and having means to compensate for differential expansion and contraction of the conductor relative to the dielectric member, while at the same time maintaining a tight housing within the dielectric member for insulating liquid.

10 A further object of the invention is to provide a fluid tight connection between the conductor and the housing which will permit expansion and contraction of the conductor without danger of leakage.

15 A further object of the invention is to provide a device of the class named which shall be of improved construction and operation.

Other objects and advantages will appear from the following description.

20 The invention is exemplified by the combination and arrangement of parts shown in the accompanying drawing and described in the following specification, and it is more particularly pointed out in the appended claims.

25 In the drawing:

Fig. 1 is a part elevation and part section showing one embodiment of the present invention.

Fig. 2 is a view similar to Fig. 1 showing a modified form of the invention.

30 In the form shown in Fig. 1, the numeral 10 designates a conductor rod which has a relatively large cross sectional area for very heavy electrical currents. The numeral 11 designates a metallic flange member which may be secured upon the top of a transformer tank or other housing for electrical apparatus to which the conductor rod 10 is connected. The rod 10 is insulated from the flange 11 by a bushing insulator comprising a sleeve 12 which extends through an opening in the flange and is provided with a shoulder 13 upon which the flange 11 is supported. A cone 14 of insulating material has its lower end supported upon the flange 11 and carries an expansion chamber 15 upon its upper end. The members 12 and 14 may be made of any suitable dielectric material, but porcelain is the material most commonly used for this class of devices. Gaskets 16 and 17 are provided to insure liquid tight joints between the flange 11 and the dielectric members. A third gasket 18 is interposed between the upper end of the cone 14 and the expansion chamber 15 to provide a tight joint at this point. An insulated flux control 19 is electrically connected with the flange 11 and projects upwardly inside the cone 14 to prevent dis-

charge from the top of the flange. As shown in the drawing, the conductor rod 10 is a plain cylindrical rod threaded at its upper and lower ends to receive terminal members. This provides a continuous conductor passing entirely through the bushing without any interruption or joints to cause heating or resistance in the path of the heavy current. A fitting 20 is threaded on the lower end of the rod and bears upon the lower end of the bushing sleeve 12, a gasket 21 being provided to insure a tight joint at this point.

The fitting 20 may be provided with a removable pipe plug at 22 to facilitate draining of the oil from the interior of the bushing. The various parts of the bushing are held tightly compressed against their gaskets by a series of helical springs 23 spaced about the interior of the expansion chamber 15 and bearing upon the bottom flange of the chamber housing. A plurality of springs spaced about the conductor 10 avoids the heating effect that would be produced by magnetic induction, due to the heavy current in the conductor, if a single steel spring were used encircling the conductor. A ring 24 rests upon the upper ends of the springs 23 and supports a flange ring 25 threaded on the upper end of the conductor rod 10. The springs 23 are held in compression by the ring 25 so that they will insure pressure on the gaskets in the various joints of the bushing. The expansion chamber 15 is provided with a cover 26 which is placed over the flange ring 25 after the bushing has been assembled and is soldered in place at 27 to insure a tight joint at this point. A removable pipe plug 28 provides means for filling the bushing with oil after it has been completely assembled.

A ring nut 29 is threaded on the upper end of the conductor rod 10 above the top of the cover plate 26, and is connected to the cover plate by an expansion bellows 30, preferably of thin sheet metal, which insures a tight closure at the top of the expansion chamber. The ring nut 29 is soldered to the upper end of the bellows 30 and the lower end of the bellows is soldered to the cap 26 and the ring 29 is also soldered to the conductor rod 10, after it has been adjusted to the proper position. This insures a tight connection between the expansion chamber and the conductor rod so that all danger of leakage is avoided. The flexible bellows 30 permits expansion and contraction of the conductor rod relative to the bushing without producing any stress upon the dielectric member or other parts of the bushing.

A breather opening 31 is provided in the ex-

55

- pansion chamber 15 to allow for expansion and contraction of the fluid inside of the bushing. The current passing through the conductor 10 may be very heavy and it is desirable that no portion of this current be shunted to the springs 23 or the wall of the expansion chamber, as current in these parts might produce undesirable heating sufficient to loosen some of the soldered joints. To avoid any such shunting effect, the inner edge of the lower portion of the expansion chamber 15 is covered by an insulating ring 32, and a similar insulation is provided at 33 between the ring 24 and the conductor. The voltage between these points, of course, is very low so that a slight insulation will be sufficient. The heavy conductor 10 passing entirely through the bushing without any interruption provides a very low resistance path for heavy currents, so that heating is reduced to a minimum and the springs 23 insure a tight fit at all of the joints between the metal and porcelain parts, and the expansion bellows 30 insures a tight joint at the top of the expansion chamber so that all danger of leakage is entirely avoided.
- 25 The form of the invention shown in Fig. 2 is quite similar to that in Fig. 1 except that in this form the conductor rod 35 does not project at the ends of the bushings but is threaded onto the terminal members which form the ends of the bushing housing. The lower terminal member 36 bears upon the porcelain sleeve 37 and is threaded onto the lower end of the rod 35. The terminal member 36 is provided with a threaded end 38 for connection with the apparatus inside of the housing on which the bushing is mounted. The housing flange 39 and cone 40 are similar to the corresponding members in Fig. 1.
- In Fig. 2 the cover cap 41 for the expansion chamber 42 is provided with terminal lugs 43 for connection with the external conductor, the cover cap 41 being threaded on the upper end of the conductor rod 35. Springs 44 bear on the bottom flange of the expansion chamber 42 and on the cover cap 41 to compress the gaskets at the joints between the parts of the bushing and insure tight fits at these points. An expansion bellows 45 connects the expansion chamber 42 and the cover 41 to allow expansion of the conductor rod 35 and maintain a tight joint at the top of the bushing, as well as to provide for relative movement of the parts under the action of the springs 44.
- In assembling the bushing shown in Fig. 2, the rod 35 may be screwed into the cover cap 41 and sweat in place by means of solder in the threaded joint. The cover cap is provided with a rib 46 which fits into a notch in the top of the lower member 42 so as to prevent relative rotation between the expansion chamber and its cover cap. Rotation of these parts relative to each other would tend to break the soldered joints at the ends of the bellows 45 or between the cover cap and the conductor. After the parts of the expansion chamber and upper end of the conductor are assembled, they are placed on the bushing and the springs 44 compressed by a suitable jig, after which the lower terminal 36 is threaded onto the lower end of the conductor so that when the jig is released, the tension of the springs 44 will hold the

bushing together and, at the same time, produce pressure on the threaded joints at the ends of the conductor rod so as to insure good electrical connection. Of course, the solder in the upper joint also insures electrical connection at this point. 5

Another method of assembling the bushing is to solder the lower threaded joint and then while the expansion chamber is held in place by a jig with the springs compressed, the conductor rod is screwed into the opening in the cover cap 41. 10 This method may also be used where the conductor rod 35 extends integrally through the lower terminal, as is shown in Fig. 1. In this case, it is of more importance to solder the lower joint in order to prevent leakage of oil through the 15 threads of the joint. To facilitate this second method of assembly, the bushing may be assembled in an inverted position.

I claim:

1. The combination with a conductor rod, of a 20 supporting flange having an opening through which said rod extends, a bushing insulator having separate portions for insulating said rod and flange, a metal spring for holding the portions of said insulator in close connection, fittings for 25 receiving the stress of said spring, and a spacer of solid dielectric material interposed between said rod and one of said fittings for insulating said one of said fittings from said conductor rod to prevent shunt currents from passing 30 through said spring.

2. The combination with a conductor rod, of a supporting flange having an opening through which said rod extends, a bushing insulator having separate parts thereof bearing on opposite 35 sides of said flange, a fitting secured to said rod and having bearing connection with one of said parts, an expansion chamber having bearing connection with the other of said parts, a metal spring for exerting pressure on said parts to hold 40 said parts together, a fitting providing bearing connection between said conductor rod and said spring, said fitting comprising a solid dielectric spacer for insulating said spring from said conductor rod, said spring also having bearing connection with said expansion chamber, and means 45 for insulating said expansion chamber from said conductor rod adjacent the bearing connection thereof with said spring.

3. In combination a conductor rod, a supporting flange having an opening through which said 50 rod extends, tubular dielectric members surrounding said rod and bearing on opposite sides of said flange respectively, an expansion reservoir bearing on one of said dielectric members, a cover 55 for said reservoir threaded on one end of said rod, a metal spring interposed between said reservoir and its cover, a fitting threaded on the end of said conductor opposite said reservoir and bearing on the other dielectric member, an expandible bellows connecting said reservoir with its cover to 60 form a liquid tight seal therebetween and means formed of solid dielectric material interposed between said conductor and said reservoir to prevent shunt currents from traversing said spring 65 and said bellows.

THOMAS F. BRANDT.
